VENTILATED GUN SIGHT RIB

Arne Y. Grahn, Warehouse Point, Conn., assignor to The Poly Choke Company, Incorporated, East Hartford, Conn.

Filed Mar. 28, 1962, Ser. No. 69,604

Term of patent 14 years

(Cl. D30—1)

FIG. 1 is a side elevational view of a ventilated gun sight rib, showing my new design;

FIG. 2 is a top plan view thereof;

FIG. 3 is a fragmentary view similar to FIG. 1 but on a somewhat larger scale; and

FIG. 4 is a sectional view taken on line 4—4 of FIG. 3.

It is to be understood that parts of the scalloped pattern in FIG. 2 have been omitted for convenience of illustration only.

The gun sight rib is shown broken away in FIGS. 1 and 2 to indicate indeterminate length, and the broken line showing of the gun barrel is for illustrative purposes only.

I claim:

The ornamental design for a ventilated gun sight rib, substantially as shown and described.
